(57) **CLAIM**

The ornamental design for a motor driven valve, as shown and described.

DESCRIPTION

FIG. 1 is a perspective view of our new design; FIG. 2 is a front elevation view thereof, the rear elevation view being a mirror image thereof;

FIG. 3 is a right side elevation view thereof;

FIG. 4 is a left side elevation view thereof, the portion inside of the broken line, including the depth thereof, forms no part of the claimed design;

FIG. 5 is a top plan view thereof; and,

FIG. 6 is a bottom plan view thereof, the portion inside of the broken line, including the depth thereof, forms no part of the claimed design.

The portions of the motor driven valve shown in broken lines form no part of the claimed design.
